UNITED STATES PATENT OFFICE.

ANTONIO VIEIRA, OF NEW YORK, N. Y., ASSIGNOR OF ONE-HALF TO ALFREDO DE LEON,
OF NEW YORK, N. Y.

DESIGN FOR A PLAQUE.

52,198.

Specification for Design.

Patented July 16, 1918.

Application filed February 2, 1918. Serial No. 215,211. Term of patent 7 years.

To all whom it may concern:

Be it known that I, ANTONIO VIEIRA, a citizen of the Republic of Colombia, and a resident of the borough of Manhattan, city, county, and State of New York, have invented a new, original, and ornamental Design for Plaques, of which the following is a specification.

The figure is a plan view of a plaque, illustrating my new design.

I contemplate the following uses to which my invention can be put, namely, it may be worn upon the person, or it may be hung upon the wall or any other suitable support, either temporarily, as pictures are usually hung, or permanently, as tablets are usually placed and secured.

I claim:

The ornamental design for a plaque substantially as shown and described.

In witness whereof I have hereunto set my hand at the borough of Manhattan, city, county and State of New York, this nineteenth day of January, 1918.

ANTONIO VIEIRA.

In presence of—

A. J. DE LEON,
ISABEL R. RICHARDS.
